UNITED STATES PATENT OFFICE.

WILLIAM ROGERS, OF HARTFORD, CONNECTICUT.

DESIGN FOR A SPOON, &c.

SPECIFICATION forming part of Design No. 19,468, dated December 3, 1889.

Application filed June 3, 1889. Serial No. 312,989. Term of patent 14 years.

To all whom it may concern:

Be it known that I, WILLIAM ROGERS, a citizen of the United States, residing at Hartford, in the county of Hartford and State of Connecticut, have invented a new and original Design for Spoons and Forks, of which the following is a specification, taken in connection with the accompanying illustrations, forming a part of the same, in which—

Figure 1 represents the front of a spoon ornamented in accordance with my design. Fig. 2 is a longitudinal section of the same. Fig. 3 is a rear view of the same, showing an ornament *f*, in high relief, affixed to the bowl.

The front or obverse side of the handle, as shown in Fig. 1, is ornamented at the tip thereof by a scroll *a*, from which starts a leaf-scroll *b*, having leaves substantially evenly divided on each side of its axis. Opposite the upper end of the leaf-scroll *b* there is a smaller scroll *c*, which nearly fills the space between the scrolls *a* and *b*. Upon the back or reverse side of the handle there is, about the middle of the distance between the ends of said handle, a leaf and scroll ornament *d*, which covers about one-half of the handle,

and at a point adjacent to the bowl there is a bunch of leaves *e*, from which the stem of a scroll *f* apparently starts; but said scroll, at the back of the bowl, at the bend thereof, is 30 in high relief.

What I claim, and desire to secure by Letters Patent, is—

1. The design herein for a spoon, having the scroll *a* at the tip of the handle shown, 35 from which starts a leaf-scroll *b*, having leaves substantially evenly divided on each side of their branch, and a scroll *c* on one side thereof, as described and shown, upon the front or obverse side of the handle. 4c

2. In a design for a spoon herein shown and described, the back or reverse side having an ornament *e* adjacent to its bowl and a scroll *f* in high relief upon the bend or base thereof, substantially as described and 45 shown.

In testimony whereof I affix my signature in presence of two witnesses.

WILLIAM ROGERS.
